UNITED STATES PATENT OFFICE.

JOHN S. DAVIS, OF TOLEDO, OHIO, ASSIGNOR TO THE TOLEDO MOWER
AND REAPER COMPANY, OF SAME PLACE.

GRAIN-BINDER.

SPECIFICATION forming part of Letters Patent No. 274,441, dated March 20, 1883.

Application filed October 12, 1882. (No model.)

To all whom it may concern:

Be it known that I, JOHN S. DAVIS, of Toledo, in the county of Lucas and State of Ohio, have invented certain new and useful Improvements in Grain-Binders, of which the following 5 is a specification.

My invention relates to improvements applicable to grain-binding machines of the class usually designated "platform-binders"—that 10 is, machines by which the grain is delivered in or nearly in horizontal paths from the grain-platforms to low-down binding-receptacles.

My objects chiefly are to insure isolation or 15 complete separation of the respective gavels of grain successively accumulated for binding from other grain carried by the machine, so preventing the entanglement or connection by straggling stalks of one bundle with another, and to insure the delivery of grain to the binding-receptacle in properly straightened and 20 even condition.

The subject-matter deemed novel will hereinafter be distinctly claimed after being described in connection with the accompanying 25 drawings, which represent a suitable application of my improvements, though showing only those parts of appropriate mechanism an illustration of which is thought to be required to convey a proper understanding of my im- 30 provements. Some of these improvements may, however, be used without the others, and also be employed in connection with mechanism differing in various respects from that shown and hereinafter particularly described.

Figure 1 is a plan view, parts being broken away and various features of a complete machine omitted. Fig. 2 is a view partly in rear elevation and partly in section on or about on the lines 2 2 of Figs. 1 and 4. Fig. 3 is a view 35 partly in rear elevation and partly in section on the lines 3 3 of Figs. 1 and 4. Fig. 4 is a side elevation. Fig. 5 is a view partly in plan and partly in section, as indicated by the lines 5 5 of Figs. 3 and 10, showing on an enlarged 40 scale a portion of the "gear-plate" or gearing-supporting front end of the binder-frame, and in part the mechanism mounted thereon. Fig. 45 6 is a detail view, partly in plan and partly in section, through the "gear-plate" on the line 6 6 of Fig. 7, showing parts of tripping mechanism through or by way of which a cut-off,

gavel-separating mechanism, and binding mechanism are thrown into action by the pressure of the grain when accumulated in sufficient quantity in the binding-receptacle; Fig. 7, a 55 view partly in side elevation and partly in section on the lines 7 7 of Figs. 1, 3, and 6, representing details of the tripping mechanism; Figs. 8 and 9, respectively, detail views in side elevation, and partly in rear elevation and 60 partly in vertical section, of other features of the tripping mechanism. Fig. 10 is a view in elevation with some parts in section, showing the inner side of the "binder-gear" or main gear by which the binder-arm, knotter, &c., 65 (the binding mechanism proper,) are actuated, the devices by which the knotter-pinion is actuated being omitted. Fig. 11 is a view partly in front elevation and partly in section on the line 11 11 of Fig. 5, showing details of the tripping mechanism and means by which parts thereof are held against accidental movement. Fig. 12 is a view showing in longitudinal section a portion of the driving-roller of the endless carrier. Fig. 13 is a rear elevation of a 70 portion of the grain-platform, &c., showing means for adjusting a series of rocking fingers by which the grain is straightened on the endless carrier.

As in this instance organized, my present 80 improvements are especially adapted for use in connection with sundry other improvements invented by me and shown in my applications Nos. 70,814 and 71,887, for United States Letters Patent for "Improvements in Grain-Binding Harvesters" and "Improvements in Band-Securing Mechanism of Grain-Binders," respectively filed September 1, 1882, and September 15, 1882. Other features, some of which are shown in connection with my present invention, and in connection with some of which my invention is suited to be used when ingrafted upon a fully-organized machine, are the same or substantially the same as devices or combinations of mechanism shown and described in connection with or as constituting the improvements claimed by me in United States Letters Patent No. 260,668, of July 4, 1882, and Nos. 261,590 and 261,591, of July 25, 1882.

I do not herein claim any improvement claimed or claimable in either of the aforesaid

applications, my present invention being limited to certain improvements herein claimed.

The finger-beam A, the grain-platform provided with a series of belts, constituting an endless carrier, A', the circular rotary butt-guide A², the platform back-beam A³, the binder-gearing and manner of actuating it, and the sills B B, gear-plate B', cross-bar or tie-piece B², tubular frame-support B³, and spanner-pieces or bridge-bars B⁴ of a light binder-frame, are, unless hereinafter otherwise described, all the same or substantially the same as heretofore elsewhere described by me. The cross-ribs or transverse cleats, commonly attached to endless carriers, are by preference omitted from the belts of the carrier A', in order that the movement therewith of the grain toward the place of delivery or binding-receptacle A⁴ may the more readily be controlled or temporarily arrested for straightening, in manner presently to be described, as well as for insuring its being properly evened at the butts by the action of the butt-guide.

The mechanism for impeding or arresting the stalks of grain in their travel with the carrier is adjustable, so as to best suit it for action in straightening the grain in the varying conditions in which it is deposited upon the carrier as cut, as well as to provide for holding it out of action when the grain does not require straightening. This straightening mechanism, as shown, consists of a series of short vertically-rocking fingers, C, secured to a rock-shaft, C', suitably mounted in the finger-beam and platform back-beam and extending between the upper and lower portions of the carrier, the fingers projecting through the spaces between the belts when set for action by a lever or crank, O², at the rear end of the rock-shaft. A rack, O³, on the back-beam engages with the lever to hold the straightening-fingers in the desired position—either out of action beneath the upper part of the carrier, or projecting more or less through the spaces between the carrier-belts. The fingers are preferably hooked or curved downwardly at their outer ends, with their range of adjustment such as never to admit of their points rising above the plane of the carrier's upper surface, for an obvious purpose. It will be understood that when the straightening-fingers are rocked into operative position, as shown, those ends of stalks of grain—either the heads or the butts—which are in advance or nearer the delivery end of the carrier than their opposite ends (a condition arising principally from the irregular way in which fallen or inclined grain is necessarily deposited upon the carrier at varying inclinations, instead of at right angles with the finger-beam) will be arrested in their movement with the belts and held by the fingers until the rearmost ends are brought up, and the stalks thus caused to lie diametrically across the carrier from its front to its rear edge, or parallel with the rock-shaft of the straightener. As the stalks are thus accumulated

they are in turn gradually raised and forced over the fingers, and while so accumulating they are acted upon by the butt-guide to even the grain at the butts.

The carrier driving-roller is actuated continuously, during the rotation of a driving-gear, D, by means of a pinion fast on the shaft a of the roller and engaged by this gear. The driving-roller of the continuously-actuated endless carrier is made in sections, being composed of a series of short wooden rolls or spools, b, corresponding in number with the belts making up the carrier and fitted and clamped upon the shaft a, so as to be held by friction against turning independently thereof. The front or first one of the series of rolls is abutted against a plain metallic disk, b', which is fitted on the shaft and held against forward movement thereon by a cross-pin, a', or by some well-known equivalent for the pin. The disk is of a diameter sufficiently greater than that of the roller proper to act as a belt-guard. Another disk b' is interposed between the rear end of the first roll and the adjacent end of the next roll, and serves as a guard against displacement of the belts between which it projects. Centrally and annularly shouldered or hubbed disks a² are arranged in pairs upon the shaft between the respectively adjacent ends of the remaining spools b, and at the rear end of the roller a shorter spool, b², abuts at its front end against the rearmost one of the last pair of disks a², and at its rear end is borne against by a disk or washer, b³. A nut, a³, screwed upon the threaded portion a⁴ of the shaft, near its rear end, is forced tightly against the washer-disk b³, thus sufficiently firmly clamping all the parts together, as well as upon the shaft, the frictional contact between the pin a' and front disk b' and the nut a³ and washer b³ holding the roller to the shaft. The reduced or tenoned rear end of the shaft a is fitted in a thimble bearing or bushing, b⁴, in the back-beam of the platform. The plain surfaces of each pair of the hubbed disks are placed next the adjacent ends of the spools, between which they are located, and their hubs abutted, so forming annular spaces between the disks from their hubs to their peripheries, for a purpose further on to be explained. Instead of the pairs of disks a², one-part annularly-grooved circular plates might be used, if preferred.

A cut-off, shown as consisting of a rock-shaft, e, having fingers e' rigidly connected to it, and a crank, e², is intermittently actuated by suitable mechanism, through or by way of a link or connecting-rod, as will hereinafter be described, so as to arrest the flow of grain when a sufficient quantity to form a gavel has accumulated in the binding-receptacle, or in it and between it and the carrier in the way E, along which the grain passes from the carrier to the binding-receptacle. The upwardly-curved fingers of this platform cut-off rest at their ends, when out of action, in the annular recesses provided in the carrier driving-roller by the

pairs of hubbed disks, and are connected with the rock-shaft by means of short arms or crank-plates c^3 , fixed to the rock-shaft and having the fingers rigidly united to them by riveting or otherwise. When elevated each cut-off finger, except the rearmost one, projects through a space between the adjacent edges of two carrier-belts, and the rear finger rocks up near the rear edge of the back belt of the carrier. 5 No cut-off finger is shown between the first and second belts of the series; but one may be employed there, if preferred, and a pair of disks, $a^2 a^2$, or the equivalent—a single grooved disk—would then be substituted for the disk b^1 . 10 No cut-off is employed in advance of the front belt, the butts of the grain not extending so far forward after being acted upon by the butt-guide. By curving the cut-off fingers and mounting them by cranks on the rock-shaft, as shown, it will be seen that the fingers, when raised, pierce through instead of lifting the mass of grain; that provision is made for arresting a greater quantity of grain than could be stopped by straight fingers projecting a corresponding distance above the carrier; that the fingers are not apt to draw stalks between the belts in descending, and that the grain is accumulated against the fingers closer to the inner end of the carrier than it would be were 25 the fingers attached directly to the rock-shaft instead of to the crank-plates. It will further be apparent that in event of injury to the fingers they can be removed by separating them from the crank-plates and necessary repairs 30 be made without loss of the crank-plates or even removing them from the rock-shaft.

The driving-gear D of the binder-gearing rotates with the bevel-pinion d , which is actuated in any suitable way, preferably as shown 40 in the before-referred-to application, No. 70,814, of September 1, 1882. An idle-pinion, d' , to which motion is imparted by the driving-gear, meshes with a gear, D' , which is fastened on the shaft d^2 of a packer, D^2 , and serves to rotate the shaft and operate the packer continuously during the actuation of the driving gear. A pinion, d^3 , attached to the gear D' on the packer-shaft, meshes with a gear, D^3 , for intermittently actuating a normally stationary 45 gear, D^4 , by the mechanism of which the binding mechanism is actuated.

The binder-gear D^4 , as heretofore fully described in connection with other of my inventions, makes one revolution each time it is thrown into action by suitable tripping and 55 clutch mechanism for binding a gavel, the tripping mechanism being actuated by the pressure exerted by the grain, and serving by its connections with the clutch mechanism to cause temporary engagement of the binder-gear with its actuating-gear D^3 .

The gear D^3 is unprovided with the heretofore employed face-spurs or side teeth for engagement with the sliding clutch-bolt F of the 60 binder-gear, this bolt being caused to engage, when slid outward, with the ordinary periph-

eral teeth of the gear D^2 . In other respects the clutch mechanism (including the means for dogging and for retracting the bolt F) is the same as before, consisting of the tripping and 70 dogging lever F' , acted upon by a spring, and provided with the catch f , the spring f' , the lever F^2 , pivoted on the binder-gear, and connected at one end with the clutch-bolt and acted upon at its opposite end by the catch end 75 of the lever F' , and the fixed cam f^2 on the frame or gear-plate B' , acting on the bolt-lever, and by which the bolt is retracted against the force of the spring f' , and its lever left engaged by the dogging and tripping lever. 80

A rock-shaft, G , means by which to operate it by the pressure exerted by the grain when accumulated to form a bundle, and connecting mechanism between the rock-shaft and lever F' , serve, as further on to be described, to 85 trip the clutch mechanism and start the binder-gear after first actuating the cut-off to elevate it and arrest the flow of grain. When the toothless portion f^3 of the binder-gear is opposite its actuating-gear and the clutch-bolt 90 retracted, the binder-gear is locked against accidental movement by the spring-brake F^3 yieldingly engaging with it.

The binder-arm rock-shaft H has the rock-ing binder-arm H' fastened to it, is mounted 95 in the rear bearing, h , and the frame-tube B^3 , and is actuated by a slotted crank, h' , and a pitman, H^2 , connecting it with the binder-gear in such way that it may be held at rest, as heretofore, while bands are being knotted about 100 bundles.

The arms of the packer rotate in longitudinal openings or slots in clearers $E' E'$, which not only serve to strip from the packer any grain which may cling to it, but also partly 105 constitute the binding-receptacle A^4 and grain passage-way E , leading thereto from the grain-platform. Each of these clearers is pivotally supported at one end on the packer-shaft by a pair of lugged sleeves, $e e$, at the sides of 110 the hub of a set of packer-arms, and at their opposite ends the clearers are adjustably secured to the binder-arm rock-shaft and to the frame-tube B^3 , respectively, so that the clearers, after being slightly rocked about the packer-shaft to raise or lower them, may be held in 115 the desired position.

The rock-shaft G of the automatic tripping or starting mechanism is mounted in bearing-lugs $g g'$ on the frame-tube B^3 , and, as in this 120 instance shown, is operated by a float-trip or vertically-vibrating starting-arm, G' , elevated by the upward pressure of the grain as accumulated in the receptacle beneath it. The starting-arm, as shown, is mounted at its heel end, 125 so as to rock freely about the packer-shaft d^2 , by means of a sleeve, g^2 , and at its outer forked end acts upon the tripping rock-shaft G . This rock-shaft is shown as provided with a crank or toe, G^2 , to be struck and elevated by the 130 starting-arm, the fork g^2 at the free end of which engages the toe and insures proper ac-

tion when the arm is forced upward by the grain. The toe G^2 is by preference adjustably secured to the rock-shaft to admit of its being set, so that the proper rocking movement may be imparted to the rock-shaft by the starting-arm when raised to any desired extent by the grain, the rock-shaft being so adapted to be actuated by larger or smaller gavels, according to the size which it may be desired to have to the bundles when bound.

Mechanism by which to separate grain for forming a bundle from other grain, and insure its delivery to the binding-receptacle or within the embrace of the binder-arm, and then completely isolate it to render it impossible for grain of one gavel to become entangled with that of another, consists, as in this instance shown, of the following devices: Two rocking "parting-arms," I I , are loosely mounted upon the packer-shaft d^2 by means of a sleeve, e' , to which they are rigidly connected, and this sleeve is provided with a rack-gear, e^2 , which is engaged by a rack-bar, I' , having suitable pivotal connection, i , at its heel end with the binder-arm near the heel end or rock-shaft H thereof. A guideway formed by a lug, i' , on one of the clearer-supporting sleeves e holds the rack-bar in engagement with the gear e^2 . Each of the parting-arms has an irregularly-curved rod, I^2 , secured to it, one end of the rod being fastened to the point or extreme outer end of the arm, and the other end secured to the arm near the heel thereof or close to the packer-shaft. The curvature of these rods I^2 I^2 is such that they do not project into or obstruct the binding-receptacle, and do not, when in their normal position, interfere with the passage of the grain along the way E as acted upon by the arms of the packer D^2 . The parting-arms are of equal length, and are longer than the arms of the packer, and the radius of curvature of each of the rods I^2 for a portion—say half—of its length about corresponds with the length of the parting-arms, these portions of the rods being concentric with the packer-shaft. For the remainder of their length the rods are eccentric, gradually nearing the packer-shaft. It will thus be seen that the rods I^2 I^2 for a portion—say two-thirds—of their length are farther from the packer-shaft than are the outer ends of the packer-arms. The rods are in this way made to act as a guard or auxiliary cut-off to prevent any grain being forced toward the binding-receptacle or acted upon by the packer when the parting-arms have been moved by the downward rock of the binder-arm into position such or about such as that in which one of them is represented by the dotted lines in Fig. 2. As the packer-arms rotate above the bottom of the way E , and within the path described by the outer end of the parting-arms, and as these arms in descending approach very closely to the endless carrier where it passes over the driving-roller to reach grain outside the path of the packer, and then project into

the slot E^2 in the bottom of the grain passage-way, so as to interpose the passage-way cut-off or packer-guard I^2 between the carrier and the packer and passage-way, while projecting beneath the bottom of the passage-way, it will be seen that grain left by the packer will be acted on by the arms, and that there is no possibility of carrying grain from the platform or carrier to or partly to the binding-receptacle, even were any straggling stalks left inside the roller of the endless carrier or inside the platform cut-off or rocking fingers c' when elevated.

Instead of the gavel-separating mechanism consisting of a pair of parting-arms and their attached guard-rods, a single arm and guard-rod may be used, if preferred. This gavel-separating mechanism, as in this instance shown, is thrown into action after the elevation of the platform cut-off fingers c' , in order not only to give the packer time to clear the way E , but that by said mechanism any grain inside these fingers, within reach of the parting-arms, which has not been carried along and forced into the binding-receptacle by the packer shall be delivered to the receptacle and held so as to be brought within the embrace of the binder arm.

Those features of the tripping and starting mechanism which actuate the cut-off to arrest the delivery of grain by the carrier preparatory to throwing the binder-arm and gavel-separating mechanism into operation are, as in this instance shown, organized as will now be described.

A normally-pendent swinging arm or downwardly-projecting crank-plate, J , is fastened to the rock-shaft G , near its front end, in advance of and close to the bearing g' . This crank-plate is two-armed, one arm, J^1 , projecting outwardly, and the other, J^2 , inwardly, or toward the grain-platform side of the machine, and carries a latch, K , acting in connection with an arm, L , hung loosely on the shaft G at its end. The latch consists of a vertically-vibrating arm connected at its heel by a pivot, k , to the arm J^2 of the crank-plate, and supported at its opposite end by a pin, k' , in a curved slot, K' , in the arm J^1 of the crank-plate. The loosely-mounted arm L is acted upon by the latch so as to be engaged and caused to swing with it until freed by the upward movement of the latch. The latch and arm are engaged by the contact of a dogging-shoulder, l , on the former, with a lug, l' , on the latter. The latch is provided with a trip-lug, L' , by which it is elevated to free the arm L , as in turn to be explained. It will be seen that so long as the pendent arm L on the rock-shaft G is dogged by the latch of the crank-plate J the arm is caused to swing with and maintain a fixed relation to the rock-shaft when acted upon as before explained, and that as soon as the latch is tripped to release the arm it is freed from control by the rock-shaft and its attachments.

The rock-shaft G is connected with a spring-

actuated dog or hook-ended bell-crank lever, M, mounted in bearings shown as formed by the supporting-lugs m m' , projecting rearwardly from the gear-plate portion B' of the binder-frame, and performing functions in turn to be explained. The connection of the rock-shaft with said dog is through or by way of the arm L, and a link or draw-bar, L², pivoted at its opposite ends, respectively, to this arm and the controlling-arm M' of the dog. The dog has two motions, being adapted to rock vertically and vibrate in a plane at a right angle with that in which it rocks. The vibratory movement of the dog is substantially horizontal. This two-motion dog has formed with or rigidly attached to it a sleeve or long hub, M², and the pivot-pin m^2 is fitted in this sleeve and fixedly fastened thereto by a removable pin, or otherwise, when the parts are in place in the bearing-lugs. The upper one, m , of these lugs is slotted, and the pivot-pin is so formed and fitted in the lower lug, m' , as to admit of the desired slight rocking motion, the upper end of the pivot playing in its bearing-slot to accommodate this motion. A spring, M³, coiled about the dog-sleeve, bears at its opposite ends, respectively, against a fixed lug, m^3 , (seen dotted in place in Fig. 5,) and a pin, m^4 , on the dog, and is thus made double-acting, one of its functions being to hold the dog rocked downward to the limit of its movement, or act with a tendency to move it into this position, as shown, and the other to act in opposition to the link L², (and another link further on described,) and hold the dog in its normal position, when the dog is freed from other control, and vibrate it into such position when released after being positively vibrated in the opposite direction.

An intermittently-actuated mutilated gear, N, loosely mounted on its shaft—in this instance the packer-shaft d²—has a vertically-rocking pawl, n, pivoted to its inner face, or that next the gear-plate B', and a ratchet, N', is fastened to the shaft, close to the mutilated gear, for engagement with the pawl when this gear is to be caused to rotate with its shaft. The pawl n (see Figs. 3 and 11) is pivoted about midway its length to the gear N, near its periphery, is provided with the usual ratchet-engaging nose, is borne against at its heel end by a spring, n', acting with a tendency to rock the pawl-nose into engagement with the ratchet or hold it engaged therewith, and has a heel arm or hook, n², normally engaged by the hook or nose of the dog M. The strength of the spring M³ is such relatively to that of the spring n' as to enable the dog to overcome the force exerted by the spring n' on the pawl. In this way the weaker spring, while serving to hold the pawl engaged with the ratchet when the dog is vibrated and the pawl released, is caused to yield to the force exerted by the stronger spring when the pawl is dogged or held in its inoperative position by the dog. The gear N makes one revolution at

each actuation, and when, upon the final portion of its revolution, the pawl is presented to the dog-nose, the dog, by the contact of its nose with the pawl between its pivot and heel, is rocked upward against the force of its spring M³, into the position in which it is represented by dotted lines in Fig. 11. When the dog is so rocked upward its pivot m^2 is moved in the slot in the bearing m , and comes to rest at the end of the slot opposite that which it is shown as occupying in the drawings. This movement of the dog to the limit of its upward rock is the result of the resistance offered to the upward rock of the pawl-nose arising from the binding contact of the nose with the ratchet and the force exerted by the spring n', as well as by the considerably decreased force at first exerted by the dog upon the pawl because of the difference in leverage when the pawl is acted upon at its heel and between its heel and pivot. The dog-nose, acting upon the properly inclined or curved portion of the pawl from or near its pivot to its heel, gradually lifts the pawl-nose, clearing it from the ratchet at the proper time. Immediately upon the release of the ratchet the force of the spring M³ overcomes that of the pawl-spring, and the pawl-nose is lifted well clear of the ratchet as the dog-pivot moves at its upper end in the slotted bearing m , thus rocking down the dog-nose. In this way wear, noise, and possibility of accidental engagement of the pawl and ratchet are prevented. The gear N actuates a mutilated pinion, O, which is given a half-revolution at each actuation. This pinion is suitably connected by a rod or pitman, P, with the crank of the cut-off rock-shaft e, and serves by one actuation to elevate the cut-off fingers c' into their operative position (seen dotted in place in Fig. 2) and by the next actuation to depress these fingers. The pinion has two regularly-formed groups of teeth, O' O², corresponding with the group of teeth P' of the gear N, and has two isolated teeth, o o', each separated at both sides from the teeth O' O² by spaces corresponding with the space between the teeth P' and the isolated tooth p of the gear N. When the pinion and gear are at rest, the isolated gear-tooth p is in contact with or close to one of the isolated teeth of the pinion. A yielding dogging-arm or spring-brake, q, serves to arrest the pinion when released by the gear N, and hold it against accidental movement. The dog-arm is fastened to the gear-plate B', is angularly bent at its outer end, and engages with one or other of two notches, q' q', in a plate or disk, Q, fastened to the hub or sleeve of the pinion O, which turns about a suitable support secured to the gear-plate.

In order that the binding mechanism shall be thrown into action subsequently to the time of elevating the cut-off, while it is retained in its elevated position, and by the operation of the above-described actuating mechanism of the cut-off, the gear N and pinion O of this

mechanism are made to act by suitable connecting mechanism upon the tripping-lever F' of the clutch-bolt, to thus start the binder-gear D⁴. This connecting mechanism serves also 5 to release the dog M by freeing the swinging arm L from the latch K, and thus relieving the link L² from pulling strain and allowing the dog to vibrate into the path of the pawl to operate thereon, as already fully described, leaving the cut-off up.

The connecting mechanism actuated by the gear N and pinion O comprises a thrust-bar, R, acted upon by a lug, r, on the gear N, and a rod or link, R', connected at one end 15 with the crank or wrist-pin r' of the pinion O, and at its opposite end with a loosely-hung swinging arm or crank, S, by being jointed outside the thrust-bar to the crank-pins, which passes through a slot, S', in the thrust-bar. 20 This swinging arm S supports one end of the thrust-bar, and is hung upon a stud on a bracket, S², attached to the gear-plate by a bolt, s², which serves also to secure in place the tubular stud-shaft of the gear D³. The opposite end of the thrust-bar is supported and guided in its reciprocations by a loop-bracket or slotted arm, S³, bolted to the gear-plate.

The latch K is tripped by the action of an incline, R², of the thrust-bar on the trip-lug L', 30 the outer end of the latch being lifted sufficiently when actuated by the thrust-bar to release the arm L, which immediately swings into its normal position as acted upon by the spring of the dog M through the connecting- 35 rod L², as this dog moves into its normal position. When the thrust-bar is in its normal or retracted position its inner or lower end is beneath the path of the striker-lug r; but when, upon an actuation of the gear N, the 40 pinion O is given a half-revolution to elevate the cut-off and cause the link R' to swing the supporting-arm S, the lower end of the thrust-bar is lifted into position to be acted upon by the lug r near the completion of the revolution 45 of the gear N, and is forced at its upper end against the lever F', so vibrating this lever against the force of its spring f' to trip the binder-gear clutch. At the same time the swinging arm L is undogged by the tripping 50 of the latch K. Obviously the slot S' of the thrust-bar must be made long enough to admit of the thrust-bar being moved by the action of the lug r a distance somewhat greater than that between the upper end of the thrust-bar 55 and the lever F'; and as this movement of the thrust-bar takes place when the crank-pin s occupies the position to which it is moved by the pull on the rod R', by the actuation of the pinion O to lift the thrust-bar, the slot must 60 be of a length about twice as great as the distance between the axes of the pinion O and wrist-pin r', plus the space occupied by the crank-pin, the distance between the lever F' and the upper end of the thrust-bar, and the 65 distance the thrust-bar has to move after striking the lever to properly actuate it. After be-

ing actuated by the lug on the gear N the thrust-bar, owing to its inclination, would naturally slide by gravity into its normal position. Its restoration to this position is, however, insured by the action of the spring-actuated lever F', which, by pressing against the end of the thrust-bar, starts it and imparts to it a downward impetus. Owing to gravity and the jolting of the machine, the thrust-bar 75 moves downward or toward the gear N when the lower end of the thrust-bar is lifted by the crank-pin. Obviously, however, a failure of the thrust-bar to move toward the gear N with the crank-pin in time to have the upper end 80 of the slot occupied by the crank-pin when the lug r acts would not affect the operation of the thrust-bar upon the latch K and lever F' otherwise than to lessen the movement of the bar in performing its office. It should be noticed that immediately upon starting the gear N operates the cut-off-actuating pinion, and that the cut-off is completely elevated before the gear has made one-fourth of its turn, while the thrust-bar is not acted upon until the gear 85 has very nearly completed its revolution. In this way the packer D² acts upon the grain within its reach inside the cut-off and delivers it to the binding-receptacle before the actuation of the gavel-separating mechanism or 90 the descent of the binder-arm. Any straggling stalks which may be left undelivered by the packer are forced into the receptacle by the parting-arms I I, when rocked downward and into the position which they are caused to 95 assume when holding the delivered grain against spreading by expansion of the compressed gavel outside the path of the binder-arm nose. The cut-off is restored to its depressed or normal position by a second actuation of the gear N, when the dog M is tripped to free the pawl n by secondary mechanism, 100 as follows: An inclined link or draw-rod, T, connects at one end with the arm M', near the point of attachment thereto of the link L², is 105 provided with a hook, t, at its opposite end, and is guided and supported by an eye-lug or slotted hanger, shown as formed with the thrust-bar guide-arm S³. (See Figs. 3 and 4.) 110 Under the organization shown the binder-gear (the actuator of the binding mechanism) 115 actuates the link T by connecting mechanism, which serves also to actuate a rocking arm, constituting a grain-retainer, gavel-compressor, and bundle-discharger, U, fast on a rock-shaft, 120 U'. In most respects the rocking arm U, shaft U', and the actuating mechanism thereof are the same as elsewhere shown and claimed by me, and to the extent so shown and claimed are not herein claimed. A crank or disk, T', 125 fast on the rock-shaft U', is provided with a striker-stud or side pin, t', for engaging the hook of the link T. At the proper time the disk T' is rocked with its shaft to cause the pin t' to act on the link and trip the dog M, so 130 that by the time the binder-arm and the gavel-separating mechanism are elevated out of the

way and the receptacle cleared of a bound bundle, grain for another bundle will be directed to the receptacle along the way E, after the downward rock of the cut-off by the pull on

5 the connecting-rod P as the pinion O makes a half-turn. The binder-gear, when first started, acts by a long edge rib or side flange, T², Fig. 10, upon the stem or lever end u of a segment-gear, u', fast to the shaft U', and moves the 10 lever from the normal position 1 into position 2, as shown by dotted lines. The corresponding slight inward movement of the compressor end of the arm U compacts the gavel and improves its shape while the binder-arm is descending and drawing the binding material tightly about the grain. The rib T² acts on the rock-shaft lever u for the greater portion of the time occupied during the descent of the binder-arm, releasing the lever in time to relieve 15 the binding-arm of too great strain when about to be locked in the knotting position and while in contact with the grain. While the knot is being tied, preferably by a vibrating knotter, such as elsewhere described and claimed by 20 me, the compressor is again actuated by the rock of the lever u from the position in which it is shown by full lines to the third position—nearly the same as that above designated position 2—as shown at 3 by dotted lines. The 25 cam-ended rib or flange U² gradually forces the lever to this position, and thus provides sufficient slack in the band about the bundle for properly forming a knot, as elsewhere fully described by me. The movement to bring the 30 lever u into position 4 (shown by dotted lines) is imparted by the segment-gear V, and serves to actuate the link T, with the result already fully explained, and to discharge the bound bundle, as will readily be understood. The 35 action of the rib T² upon the lever u imparts the final movement to the lever to restore it to its normal position at the completion of a revolution of the binder-gear. While the knot is being tied in the band about a bundle the 40 binder-arm is locked at its nose by the engagement with the shoulder w' of a yieldingly-mounted dog, w, on a rock-shaft, W. The rock-shaft U', when in its normal position, is dogged by an arm, V', on the rock-shaft W, acting 45 against a shoulder, v', on a disk, W', secured to the shaft U'. A crank-arm, Y, on the end of the dogging-shaft W, is acted upon at the proper time by a rib, y, on the outer face of the binder-gear, so as to rock this shaft against 50 the force of its spring Y', and so release the binder-arm and the rock-shaft U', preparatory to the actuation of the latter by the segment on the binder-gear.

The dogging mechanism just above described is shown, fully described, and claimed elsewhere by me, and is not therefore herein claimed by itself or otherwise than in different combinations or connections not heretofore shown.

55 The actuating mechanism of the knotter, consisting in part of the pinion Z on the knot-

ter-shaft and the segment-gear Z' on the binder-gear, needs no description here, as this mechanism is elsewhere shown and claimed, and is not herein claimed.

When the machine is in operation, as will readily be understood from the above description and the drawings, a double precaution is taken (by the employment of the platform cut-off actuated before the starting of the binding mechanism and by the parting-arms) against the delivery of grain to the passage-way or to the action of the packer after the binding mechanism is started, while the still further precaution taken by the employment of the packer-guarding and passage-way cut-off mechanism prevents the carrying along the passage-way of any slightly delayed or temporarily lodged or entangled stalks which may have escaped or resisted the action of the packer and parting arms. The tying together of bundles by connecting stalks, and the consequent injurious effects—such as dragging of bundles over the stubble, loss of grain, derangement of bundles, or breaking of bands—are by my improvements rendered impossible.

I claim as of my invention—

1. The combination of the platform carrier-belts and the series of short curved fingers projecting through the spaces between the 95 belts and slightly above the upper surface of the carrier, said fingers having their points beneath the plane of the upper surface of the carrier and serving to temporarily arrest and straighten the grain, substantially as hereinbefore set forth.

2. The combination, substantially as hereinbefore set forth, of the carrier-belts and the adjustable grain-straightening fingers, for the purpose described.

3. The combination, substantially as hereinbefore set forth, of the carrier-belts, the grain-straightening fingers, their rock-shaft, and means for adjusting said shaft to raise or lower the fingers.

4. The combination of the carrier-belts, the grain-straightening fingers, their rock-shaft, the adjusting-lever, and the rack, substantially as and for the purpose hereinbefore set forth.

5. The combination, substantially as hereinbefore set forth, of the carrier-belts, the grain-straightening mechanism, and the butt-guide acting upon the grain while temporarily arrested by the straightening mechanism.

6. The combination of the carrier-roller shaft, the series of rolls thereon, and the pairs of hubbed disks (or their specified equivalent) between the rolls, substantially as and for the purpose hereinbefore set forth.

7. The combination of the carrier-roller shaft provided with the cross-pin and screw-thread, the series of rolls, the disks and pairs of disks between the rolls, the washer-disk, and the nut, substantially as and for the purpose hereinbefore set forth.

8. The combination of the carrier-belts,

- their driving-roller, the disks by which annular recesses are provided in said roller, and the rocking cut-off fingers, substantially as and for the purpose hereinbefore set forth.
- 5 9. The combination of the platform carrier-belts, the cut-off fingers, their rock-shaft, and the crank-plates to which the fingers are connected, and by which they are secured to the rock-shaft, as and for the purpose set forth.
- 10 10. The combination of the platform carrier-belts, the upwardly-curved cut-off fingers, their crank-plates, and the rock-shaft, as and for the purpose set forth.
- 15 11. The combination of the rock-shaft of the starting mechanism, the toe of said rock-shaft, and the float-trip acting by its free end upon the toe when forced upward by the pressure of the grain, as and for the purpose set forth.
- 20 12. The combination of the rock-shaft of the starting mechanism, the float-trip, by the free end of which the rock-shaft is actuated, and the packer-shaft, about which the float-trip vibrates, substantially as and for the purpose described.
- 25 13. The combination of the packer, the binding-receptacle, the float-trip vibrating about the packer-shaft, the rock-shaft of the starting mechanism, and its toe acted upon by the free end of the float-trip, substantially as and for the purpose hereinbefore set forth.
- 30 14. The combination, substantially as hereinbefore set forth, of the binding-receptacle, the way leading thereto, mechanism for delivering the grain to the way, the packer acting upon the grain above the bottom of the way, and the rocking parting arm, or arms, projecting beneath the bottom of the way, when rocked downward, and acting upon grain which may have escaped the action of the packer to deliver it to the binding-receptacle.
- 35 15. The combination of the packer, its rotating shaft, the way having the slotted bottom, means for delivering the grain to the way, and the intermittently-actuated rocking parting arm, or arms, mounted upon the packer-shaft, reaching outside the path of the packer-arms, and projecting into the slot in the bottom of the way, substantially as and for the purpose hereinbefore set forth.
- 40 16. The combination, substantially as hereinbefore set forth, of the binding-receptacle, the way leading thereto, means for delivering the grain to the way, the packer, and the intermittently-actuated guard or cut-off for the way rocking about the packer-shaft, for the purpose described.
- 45 17. The combination, substantially as hereinbefore set forth, of the carrier, the way to which the grain is delivered thereby, the intermittently-actuated rocking parting arm, or arms, and the cut-off rod, or rods, secured thereto.
- 50 18. The combination, substantially as hereinbefore set forth, of the rotating packer, its shaft, the parting arm, or arms, rocking about the packer-shaft, and extending farther there-
- from than do the arms of the packer, and the irregularly-curved guard rod, or rods, secured to the parting arm, or arms, and the radius of curvature for a portion of the length of which is such as to bring the packer-arms within the path described thereby, for the purpose described.
- 55 19. The combination, substantially as hereinbefore set forth, of the rocking binder-arm, the rotating packer, the packer-shaft, the parting-arms, the guard-rods, the carrier, the way, and the binding-receptacle.
- 60 20. The combination, substantially as hereinbefore set forth, of the platform grain-delivering mechanism, the platform cut-off, the way to which the grain is delivered, means for forcing the grain along the way, binding mechanism, the cut-off of the way, means by which it is thrown into action after the actuation of the platform cut-off and retained in its operative position while a bundle is being secured, and means by which the platform cut-off is thrown into action preparatory to the actuation of the binding mechanism and retained in its operative position while a bundle is being secured, for the purpose described.
- 65 21. The combination of the binding-receptacle, the way leading thereto, means for delivering grain to the way from the platform, mechanism for forcing the grain along the way and packing it in the binding-receptacle, and intermittently-actuated gavel-isolating mechanism, (11²), acting upon the accumulated grain, preventing the delivery of grain to the way, and guarding the packing mechanism, substantially as and for the purpose hereinbefore set forth.
- 70 22. The combination, substantially as hereinbefore set forth, of the binding-receptacle, the way leading thereto, means for delivering grain to the way from the platform, the platform cut-off, mechanism for forcing the grain along the way and packing it in the binding-receptacle, intermittently-actuated gavel-isolating mechanism preventing the delivery of grain to the way and guarding the packing mechanism, and means by which the platform cut-off is actuated before the actuation of the gavel-isolating mechanism, for the purpose described.
- 75 23. The combination, substantially as hereinbefore set forth, of the platform cut-off, the way by which the grain passes to the binding-receptacle, the cut-off of the way, and mechanism actuated by the pressure of the grain, by which said cut-offs are actuated, for the purpose described.
- 80 24. The combination, substantially as hereinbefore set forth, of the cut-off, the binding mechanism, the gavel-isolating mechanism, and mechanism actuated by the pressure of the grain, by which the cut-off is actuated to arrest the grain, and by which the binding mechanism and gavel-isolating mechanism are thrown into action after the actuation of the cut-off, for the purpose described.
- 85 25. The combination, substantially as here-

inbefore set forth, of starting and tripping mechanism actuated by the pressure of the grain upon the accumulation of a gavel, the platform cut-off, its actuating mechanism thrown into operation by the starting mechanism, binding mechanism, and connecting mechanism by which the binding mechanism is thrown into action by the operation of the actuating mechanism of the cut-off, for the purpose described.

26. The combination of the cut-off, the starting rock-shaft, the loosely-mounted arm thereon, mechanism by which the arm is locked to and released from the rock-shaft, and mechanism connecting said arm with the actuating mechanism of the cut-off, substantially as and for the purpose hereinbefore set forth.

27. The combination of the starting rock-shaft, the loosely-mounted arm thereon, mechanism by which the arm is locked to and released from the rock-shaft, the cut-off, its actuating mechanism, means for controlling the operation of said actuating mechanism connected with the rock-shaft arm, and mechanism operated by the actuating mechanism of the cut-off to free said arm from the rock-shaft, substantially as and for the purpose hereinbefore set forth.

28. The combination of the starting rock-shaft, the crank-plate thereon, the latch carried by the crank-plate, the arm loosely mounted on the rock-shaft and dogged by the latch, means by which said arm is connected with mechanism for actuating the cut-off, and means for tripping the latch to release the arm, substantially as and for the purpose hereinbefore set forth.

29. The combination, substantially as hereinbefore set forth, of the starting rock-shaft, the link-rod having connection therewith, the spring-actuated dog connected with the link-rod, the loosely-mounted actuating-gear of the cut-off, the ratchet fast on the shaft of said gear, and the pawl mounted on said gear, acted upon by the dog, and engaging the ratchet when released, for the purpose described.

30. The combination of the starting rock-shaft, its loosely-mounted arm, the crank-plate fast on the rock-shaft, the latch of the crank-plate for dogging and releasing the arm, the link-rod connected with the arm, the rocking and vibrating dog with which the link-rod connects, and the pawl and ratchet of the mechanism for actuating the cut-off acted upon by the dog, substantially as and for the purpose hereinbefore set forth.

31. The combination of the two-motion dog, the spring acting with a tendency to hold the dog in its normal position, the pawl acted upon by the dog, the loosely-mounted gear to which the pawl is pivoted, the ratchet fast on the gear-shaft, means for rotating said shaft, dog-actuating mechanism for releasing the pawl and causing engagement of the ratchet with the gear, and means by which to free the dog from the control of its actuating mechanism

for operating the pawl to throw the gear out of action, substantially as hereinbefore set forth.

32. The combination of the two-motion dog, 70 the dog-bearings, one of which is slotted, the pivot-pin fitted in the bearings and to which the dog is fastened, the spring acting on the dog and serving to yieldingly hold it against movement either by the turning of its pivot or 75 the play thereof in the slotted bearing, and the arm by which to actuate the dog, substantially as and for the purpose hereinbefore set forth.

33. The combination, substantially as hereinbefore set forth, of the intermittently-actuated mutilated gear, the mutilated pinion to which a half-revolution is imparted at each actuation of the gear, the cut-off fingers, their rock-shaft, and the rod connecting the rock-shaft and pinion, for the purpose described. 80

34. The combination, substantially as hereinbefore set forth, of the rocking cut-off fingers, the mutilated pinion, mechanism connecting the cut-off with said pinion, the intermittently-actuated mutilated gear, by which the pinion 90 is given a half-revolution at each operation, and means for actuating the gear, for the purpose described.

35. The combination of the intermittently-actuated mutilated gear provided with the 95 group of teeth and the isolated tooth, means for throwing the gear into and out of action, the mutilated pinion operated by the gear and having two groups of teeth and two isolated teeth, and means by which the pinion is yieldingly dogged after each half-revolution imparted to it by the gear, substantially as and for the purpose hereinbefore set forth.

36. The combination of the pinion O, making a half-turn at each actuation, means for intermittently actuating the pinion, the dogging-arm and disk by which the accidental movement of the pinion is prevented, the platform cut-off, and mechanism connecting it with the pinion, substantially as and for the purpose hereinbefore set forth. 105

37. The combination, substantially as hereinbefore set forth, of the binder-gear, its clutch-bolt, the bolt-tripping mechanism, the cut-off-actuating mechanism, and connecting mechanism by which the clutch-bolt is tripped from the actuating mechanism of the cut-off, for the purpose described. 115

38. The combination, substantially as hereinbefore set forth, of the clutch-tripping lever, the thrust-bar acting thereon, and the actuating mechanism of the cut-off by which the thrust-bar is operated, for the purpose described. 120

39. The combination, substantially as hereinbefore set forth, of the rock-shaft of the starting mechanism, the loosely-hung arm thereon, mechanism by which the arm is locked to the rock-shaft, the thrust-bar acting on said locking mechanism to release the arm, and the actuating mechanism of the cut-off by which the thrust-bar is operated. 125

40. The combination, substantially as hereinbefore set forth, of the rock-shaft of the starting mechanism, the loosely-mounted arm thereon, the crank-plate fast to the rock-shaft, the 5 latch carried by the crank-plate and acting on the arm, the thrust-bar provided with an incline for tripping the latch to free the arm, and the actuating mechanism of the cut-off by which the thrust-bar is operated, for the purpose described.

41. The combination of the thrust-bar, its swinging support, the intermittently-actuated mutilated gear provided with the striker-lug for acting on the thrust-bar, the mutilated pinion, to which is imparted a half-revolution by 15 said gear at each actuation, and the link connecting the pinion and the swinging support of the thrust-bar, substantially as and for the purpose hereinbefore set forth.

42. The combination of the thrust-bar, slotted at one end, the swinging support provided with the crank-pin passing through the slot of the thrust-bar, the supporting-arm for the opposite end of the thrust-bar, the gear having the lug for operating the thrust-bar, the link connected with the crank-pin of the swinging support, and the pinion with which the link connects, substantially as and for the purpose hereinbefore set forth.

43. The combination, substantially as hereinbefore set forth, of starting and tripping mechanism actuated by the pressure of the grain, the cut-off, its actuating mechanism thrown into operation by the starting mechanism, binding mechanism, connecting mechanism by which the actuating mechanism of the binding mechanism is thrown into action by the operation of the actuating mechanism of the cut-off, secondary mechanism by which the actuating mechanism of the cut-off is again thrown into action, and mechanism connecting said secondary mechanism with the mechanism which actuates the binding mechanism, for the purpose described.

44. The combination, substantially as hereinbefore set forth, of the cut-off, its actuating mechanism, the dog by which the operation of said actuating mechanism is controlled, the rod T, connected with the dog, and the rock-shaft actuated by the binder-gear, and with

which said rod is connected, for the purpose described.

45. The combination of the actuating mechanism of the cut-off, the dog by which its operation is controlled, the rod connected at one end with said dog, the disk acting on the opposite end of the rod, the rock-shaft to which the disk is fastened, the binder-gear, its rack, and the segment-gear of the rock-shaft operated thereby, substantially as and for the purpose hereinbefore set forth. 60

46. The combination of the rock-shaft U', the disk secured thereon, its striker-stud, the hook-ended rod operated by engagement with the stud, and the dog with which the rod connects, substantially as and for the purpose hereinbefore set forth. 65

47. The combination, substantially as hereinbefore set forth, of the rocking cut-off, its actuating mechanism, the dog by which the operation of said mechanism is controlled, the rod L², connected with the dog, means by which the rod is operated to actuate the dog for throwing said mechanism into operation to elevate the cut-off, the rod T, connected with the dog, and means by which this rod is operated to actuate the dog for throwing the actuating mechanism of the cut-off into operation to depress the cut-off. 70

48. The combination of the rock-shaft U', 80 its actuating mechanism, the disk T', fastened to the rock-shaft, the dog-actuating rod operated by the disk, the disk W', also fastened on the shaft U', the dogging rock-shaft W, its arm acting on the disk W', and means by which 85 said dogging rock-shaft is controlled and actuated, substantially as and for the purpose hereinbefore set forth.

49. The combination of the compressor, its rock-shaft, the lever and segment-gear secured 90 to said shaft, and the binder-gear provided with the long edge rib, the flange U², and the segment-gear, substantially as and for the purpose hereinbefore set forth.

In testimony whereof I have hereunto subscribed my name. 95
